United States Patent Office

Des. 189,165
Patented Nov. 1, 1960

189,165

COVER FOR A CARAFE OR THE LIKE

David J. Freiman, Corning, N.Y., assignor to Corning
Glass Works, Corning, N.Y., a corporation of New York

Filed Sept. 9, 1958, Ser. No. 52,584

Term of patent 14 years

(Cl. D58—26)

Fig. 1 is a top plan view of a cover for a carafe or the like embodying my new design.

Fig. 2 is a side elevational view of the same.

Fig. 3 is a sectional view taken on line 3—3 of Fig. 1.

I claim:

The ornamental design for a cover for a carafe or the like, as shown.
